UNITED STATES PATENT OFFICE

KARL M. YOST, OF SOUTH BEND, INDIANA, ASSIGNOR TO BENDIX BRAKE COMPANY,
OF SOUTH BEND, INDIANA, A CORPORATION OF ILLINOIS

BRAKE SHOE

Application filed March 14, 1928. Serial No. 261,453.

This invention relates to brake shoes, and is illustrated as embodied in an internal expanding automobile brake. An object of the invention is to provide a simple and inexpensive reinforced steel shoe, preferably made of steel stampings.

Various features of novelty relate to forming reinforcing plates at one end of the shoe to give a broadened thrust surface and to carry a transverse pin, and to forming reinforcing plates at the other end of the shoe with a novel pivot bearing and to other novel and desirable features of construction which will be apparent from the following description of the illustrative embodiments shown in the accompanying drawing, in which:

Figure 1 is a side elevation of the shoe;

Figure 2 is an inside elevation of the shoe;

Figure 3 is a side elevation of one of the reinforcing plates;

Figure 4 is a side elevation of another reinforcing plate; and

Figure 5 is a view corresponding to the lower end of Figure 2, but showing a modified form of pivot bearing.

The illustrated shoe includes a body portion built up by welding together at intervals an outer cylindrical rim or band 12 (to which brake lining 14 may be riveted or otherwise secured) and a central stiffening web 10, both rim and web preferably being steel stampings. This construction is more fully described, and is claimed, in Patent No. 1,659,368, granted Bendix Brake Company on February 14, 1928, on an application filed by Leland E. Long.

At the one end of the shoe, the web 10 is reinforced by two plates or stampings 16, projection-welded or otherwise secured to the opposite sides of the web. Plates 16 and web 10 are shown formed with registering open notches 18, facing toward the end of the shoe, which notches are adapted to receive a brake-applying thrust device. The plates 16 are spread in opposite directions away from web 10 at the end of the shoe, to give a wide bearing for the thrust device. Adjacent the other ends of plates

16, registering openings 19 are formed in the two plates and the web, for a suitable steady rest. An opening 20 is provided in the web, for the attachment of a return spring, a portion of the web projecting from between plates 16 for this purpose. A pin 22 is pressed through registering openings 24 in the plates and the web, for engagement with a positioning device. Pin 22 has a collar 26 engaging one face of the shoe, and has a flange 28 peened over against the other side of the shoe.

At the other end of the shoe, reinforcing plates 30 are projection-welded or otherwise secured to opposite sides of the shoe web, to form a triple-thickness arm at the end of the shoe. Registering openings 32 formed in the web and plates are provided, similar to openings 18, for a suitable steady rest. Oppositely-drawn tubular bosses 34 on plates 30 are arranged to register with an opening 36 in web 10, to form a pivot bearing of considerable length. As shown in Figure 5, in place of bosses 34, a separate bushing 38 may be provided with a collar 40 engaging one side of the shoe, and with a flange 42 peened over against the other side of the shoe.

While two illustrative embodiments have been described in detail, it is not my intention to limit the scope of the invention to those particular embodiments, or otherwise than by the terms of the appended claims.

I claim:

1. A brake shoe having a central stiffening web, and reinforcing plates secured to opposite sides of said web at one end of the shoe, the ends of said plates being flared in opposite directions and formed with registering notches opening toward the end of the shoe.

2. A brake shoe having a central stiffening web and reinforcing plates secured to opposite sides of said web at one end of the shoe, the plates and web being formed with registering notches opening toward the end of the shoe, and the notched ends of the plates being in spaced relation to the web.

3. A brake shoe having a central stiffening web and reinforcing plates secured to opposite sides of said web at one end of the

shoe, the ends of the plates adjacent the end of the shoe being spread away from the web.

4. A brake shoe having a stiffening web, reinforcing plates secured to opposite sides 5 of the web having offset end portions arranged in spaced relation to the web.

5. A brake shoe having a central stiffening web, reinforcing plates secured to opposite sides of the web at one end thereof, and offset 10 portions on the reinforcing plates arranged in spaced relation to the web, the web and offset portions having registering notches.

15 In testimony whereof, I have hereunto signed my name.

KARL M. YOST.
